DESIGN FOR AN INDICATOR DIAL CASING OR SIMILAR ARTICLE

George E. Ford, Rochester, N. Y., assignor to
Rochester Manufacturing Co., Inc., Rochester,
N. Y., a corporation of New York

Application December 18, 1939, Serial No. 88,989

Term of patent 7 years

To all whom it may concern:

Be it known that I, George E. Ford, a subject of the King of Great Britain, residing at Rochester, in the county of Monroe and State of New York, have invented a new, original, and ornamental Design for an Indicator Dial Casing or Similar Article, of which the following is a specification, reference being had to the accompanying drawing, forming a part thereof.

In the drawing:

Fig. 1 is a view in front elevation of an indicator dial casing or similar article showing my new design;

Fig. 2 is a view in side elevation of the same, and

Fig. 3 is a top plan view of the same.

I claim:

The ornamental design for an indicator dial casing or similar article, as shown.

GEORGE E. FORD.
